DESIGN FOR A SAW HANDLE

Keyes W. Atkins, Indianapolis, Ind., assignor to
E. C. Atkins and Company, Indianapolis, Ind.,
a corporation of Indiana

Application August 28, 1939, Serial No. 86,913

Term of patent 14 years

To all whom it may concern:

Be it known that I, Keyes W. Atkins, a citizen
of the United States, residing at Indianapolis, in
the county of Marion and State of Indiana, have
invented a new, original, and ornamental Design
for a Saw Handle, of which the following is a
specification, reference being had to the accom-
panying drawing, forming part thereof.

Fig. 1 is a side elevation of a saw handle show-
ing my new design;

Fig. 2 is a top plan thereof; and

Fig. 3 is a rear elevational view.

I claim:

The ornamental design for a saw handle, as
shown.

KEYES W. ATKINS.
